UNITED STATES PATENT OFFICE.

FREDERICK G. FOLBERTH, OF CLEVELAND, OHIO.

ATTACHMENT FOR HYDROCARBON-ENGINES.

1,142,951.

Specification of Letters Patent. Patented June 15, 1915.

Application filed July 14, 1911. Serial No. 638,536.

To all whom it may concern:

Be it known that I, FREDERICK G. FOLBERTH, a citizen of the United States, and resident of Cleveland, in the county of 5 Cuyahoga and State of Ohio, have invented certain new and useful Improvements in Attachments for Hydrocarbon-Engines, of which the following is a specification.

The present invention relates to an attachment for motor vehicles, being an improvement in power tire pumps of that character or type referred to in an earlier application Serial Number 594,526, filed November 28, 1910, in which the pump is adapted to be 15 actuated directly by, without having its piston connected with, the piston in a cylinder of the vehicle engine.

The particular object of the present invention is to provide a construction in which 20 the pump is adapted to be detachably connected with a relief cock such as is commonly provided on the heads of cylinders of internal combustion engines.

In the accompanying drawings: Figure 1 25 is an elevation of a portion of a cylinder of a motor vehicle engine having an embodiment of the invention applied thereto; Fig. 2 is a vertical sectional view; Fig. 3 is a view in elevation with the pump removed.

30 In the drawings 1 indicates the cylinder of a motor vehicle engine shown as provided with a water jacket 2, extending over its head, and a piston 3. As the invention is adapted to be applied to engines of various 35 forms and types the parts of the engine herein referred to are illustrated merely conventionally.

40 4 is a relief cock which is connected with the top of the cylinder and communicates with the internal chamber thereof above the piston 3 in the well-known manner. The particular form of pet cock illustrated differs from those commonly employed in having an internally threaded socket 5 formed 45 at its outer end about the bore or passage through which it communicates with the interior of the engine cylinder when its plug is in open position, and such socket is surrounded by a flange 6 providing a seat for 50 the support of the air pump.

The pump illustrated comprises a cylindrical barrel 7 provided at its outer end with the inlet and outlet valves 8, 9, the latter communicating with a pipe 10 adapted 55 to be connected, as by a flexible tube 11, with

the inflating valved tube of a tire. At its lower end the pump is provided with a tubular extension 12 adapted to enter the socket 5 in the relief cock and having a reduced section 13 adapted to extend into the 60 passage or duct in said cock substantially to the seat for the turning plug 14 thereof. The section 12 of the tubular extension on the pump is provided with a thread adapted to engage the thread in the socket 5 so 65 that by a slight turning movement the pump may be firmly secured to or detached from the cock 4. The stem 15 of the pump piston is of such diameter that it extends freely through the extension on the pump and is 70 adapted to pass through the opening in the plug 14 of the relief cock and through the passage leading from such plug to the interior of the engine cylinder 1. Said stem 75 is of such length that when the piston connected thereto is at the desired upward limit of its movement the lower end of the stem will contact with the engine piston 3 when the latter has reached the limit of its upward stroke. A coiled spring 16, arranged within the pump barrel and having its ends connected respectively with the piston and the lower end of such barrel, is adapted to maintain the stem 15 in contact 80 with the engine piston 3 throughout the 85 stroke of the latter.

The flexible tube 11 may be provided with a pressure gage 18 so that when the pump is in operation the user can readily determine the pressure which has been produced 90 in the tire being inflated.

It will be seen that the improved attachment can be easily and quickly applied to or detached from the relief cock without in any manner affecting the connection between 95 such cock and the engine cylinder.

The construction provides a relatively long or extended guide for the stem of the pump piston.

The attachment is very light and compact 100 and by its use absolutely pure air is supplied to the tire and any desired pressure can be obtained.

Having thus described the invention, what I claim and desire to secure by Letters Patent is:

1. The combination with the cylinder of a motor vehicle engine, of a relief cock secured in the head of the cylinder, a portable pump, comprising a cylinder provided with 110

inlet and outlet ports and means detachably engaging the relief cock, and a piston, the stem of which extends through the cock into the interior of the engine cylinder, and 5 means for holding the stem of the pump piston in contact with the engine piston.

2. The herein described attachment for motor vehicle engines comprising an air pump having a cylinder provided with suitable inlet and outlet ports and means for detachably engaging the outer end of a relief cock on an engine cylinder, a piston, the stem of which projects at all times beyond one end of the cylinder and is adapted to extend through the passage in said relief cock into contact with the engine piston, and 15 means acting to project said piston stem from the pump cylinder to its maximum extent.

20 3. The combination with the cylinder of a

motor vehicle engine, of a relief cock secured in the head of the cylinder and provided at its outer end with an internally threaded seat, a portable pump, comprising a cylinder provided with inlet and outlet 25 ports and having at one end a tubular threaded portion adapted to be secured in said seat, at the outer end of the relief cock, a piston within said cylinder and having its stem extending through the relief cock into 30 the engine cylinder, and means for holding the stem of the pump piston in contact with the engine piston.

In testimony whereof I affix my signature in presence of two witnesses.

FREDERICK G. FOLBERTH.
